CLAIM

The ornamental design for the blow dryer holder, as shown and described.

DESCRIPTION

FIG. 1 illustrates a perspective view of a blow dryer holder; FIG. 2 illustrates a front side elevational view thereof; FIG. 3 illustrates a rear side elevational view thereof; FIG. 4 illustrates a right side elevational view thereof; FIG. 5 illustrates a left side elevational view thereof; FIG. 6 illustrates a top plan view thereof; and, FIG. 7 illustrates a bottom plan view thereof.
The broken lines show portions of the blow dryer holder that form no part of the claimed design.
